UNITED STATES PATENT OFFICE

LOUIS STANGE, OF SOMMERDA, GERMANY, ASSIGNOR TO RHEINISCHE METALLWAAREN- UND MASCHINENFABRIK, OF DUSSELDORF- DERENDORF, GERMANY

AUTOMATIC FIREARM

Application filed June 18, 1929, Serial No 371,881, and in Germany November 15, 1928.

In automatic firearms, in which the breech piece is movable in the axial direction and in which the stock is applied to the shoulder of the firer, it is important that the weapon, 5 besides having a convenient external form, should be also protected against the entrance of foreign bodies into the internal parts displaced on firing. In order to shorten the length, it has been previously proposed to 10 make the stock hollow and to constitute the rear guiding member of the recoiling breech piece.

Such apparatus, in addition to satisfactory sealing of the internal parts, should also be 15 provided with means for ensuring easy access to the parts of the weapon to be protected, more especially the parts of the breech, in order to clean and exchange parts that have become worn, in case of obstructions on firing 20 and to exchange the barrel.

The invention obtains these results, without introducing any upwardly hinged portions of the wall of the casing which would make the weapon cumbrous, by connecting the 25 stock, forming one part of and the rear closing member of the breech casing, with or without the guide for the breech piece, so that it can at any time be easily disconnected from the other parts of the casing containing the 30 trigger, the breech sleeve and the barrel, and after removing the stock the casing can be opened at the rear end and the parts contained therein be easily accessible and removable.

Figure 1 of the accompanying drawings illustrates partly in section an automatic rifle according to the invention with the parts in the position ready for firing;

Figure 2 shows the stock with the breech 40 piece separated from the barrel.

a is the cylindrical casing, *e* a ring on which the trigger *b* with a hand grip *c*, the sight *d* and the magazine holder, which is not visible, 45 are secured. The barrel casing *f* is connected to the front portion. The barrel with the breech sleeve is mounted in the casing *a* in known manner so as to be displaceable in the longitudinal direction. The breech piece *g*, 50 which can be locked with the breech sleeve

by suitable devices, for example by rotary ribs, is guided longitudinally in the sleeve.

The neck of the stock *h* forms a rear continuation of the casing and engages with a sleeve *h'* in the casing *a* and is locked thereto 55 by a bayonet joint *h₂*, *a₁*. A locking member *h₃*, mounted in the stock so as to be elastically pressed in the radial direction, by entering into a notch of the casing *a*, locks the latter and also the stock *h* in the coupling position 60 against relative backward rotation when freed. The locking member *h₃* is removable by means of a head *h₄* projecting from the stock and operated by finger pressure.

The stock *h* has in the extension of the bore 65 of the barrel a rectilinear longitudinal boring provided with a sleeve *h₅*, which forms the rear guiding member for the breech piece *g* as it returns after firing into the stock. In the sleeve *h₅* there is at its rear portion a 70 spring *i*, which drives the breech piece forward into the closed position.

The weapon is of the type in which the breech piece is secured in its rear position ready for firing by a locking member released 75 by the trigger and, when the trigger is pressed, is impelled forward, introduces a cartridge into the barrel and then directly after ignites it.

The locking member *h* for holding the 80 breech piece after its return movement is mounted according to the invention in the stock *h* which is removable from the casing *a* of the weapon. It forms an elbow lever, of which one arm *k'* projects downwards 85 from the stock, and engages with the rod *l* displaceable in the casing *a* and is drawn backwards by the trigger *b*.

For securing the breech piece in the stock 90 for its removal with the latter, a locking device, which can be released at any time by hand, is provided therein, and the locking member for holding the breech piece, or in other types of weapon the firing pin, in the stressed position before firing can be mounted 95 in the usual manner in the casing of the weapon.

As shown in Figure 1, the breech piece *g* is guided in its return path in the stock and is held in its rear end position by the member 100

k, whereupon the weapon is ready for firing. If, for example, the barrel is to be exchanged, the locking member *h*₃ between the stock *h* and the casing *a* is released by the pressure of the finger, the stock *h* is then rotated relatively to the casing *a* until the bayonet joint *h*₂, *a*₁ is unlocked and the stock is drawn backwards in the longitudinal direction. After the separation of the stock *h* (Figure 2) with

10 the parts secured therein and the breech piece *g* from the weapon, the casing is open at the rear and the breech sleeve with the barrel can be drawn out, for exchange, rearwards from the casing *a*. The separation of the breech

15 piece from the breech sleeve and barrel, effected on opening the casing of the weapon, advantageously reduces the time required for exchanging the barrel. Obviously, the stock *h* could be removed by itself from the weapon.

20 The return movement of the breech in the stock, which on firing takes place in a perfectly straight line in the prolongation of the bore of the barrel, excludes the known canting of the weapon which occurs with arrangements which by means of curved guides return the breech piece downwards into the stock. The shoulder of the firer receives the recoil directly in the direction of this recoil so that the gun is not moved on firing.

25 I claim:

1. In an automatic firearm in combination, a longitudinally movable breech piece, a hollow stock guiding said breech piece, a casing, containing a trigger, a breech sleeve and a barrel, and means for releasably and removably connecting said stock to said casing.

2. In an automatic firearm in combination, a longitudinally movable breech piece, a hollow stock guiding said breech piece, a locking member mounted in said stock and cooperating with said breech piece, a casing, containing a trigger, a breech sleeve and a barrel, and means for releasably and removably connecting said stock to said casing.

3. In an automatic firearm in combination, a longitudinally movable breech piece, a hollow stock guiding said breech piece, a locking member mounted in said stock and cooperating with said breech piece, a casing, containing a trigger, a breech sleeve and a barrel, and means for releasably and removably connecting said stock to said casing, said locking member holding the breech piece in its return position in said stock when the weapon is assembled and may be released by said trigger for firing.

4. In an automatic firearm in combination, a longitudinally movable breech piece, a hollow stock, a sleeve mounted in said stock for guiding said breech piece, a casing containing a trigger, a breech sleeve and a barrel, means for releasably and removably connecting said stock to said casing, a locking member mounted in said stock for holding the breech piece in its return position in said

stock when said stock and said casing are connected together, and means for releasing said locking member by said trigger for firing, said sleeve in said stock forming a linear extension of said sleeve in said casing.

70 In testimony whereof I have affixed my signature,

LOUIS STANGE.
